CLAIM

The ornamental design for a tissue box, as shown and described.

DESCRIPTION

FIG. 1 is a top plan view of a tissue box showing my new design, the dashed lines showing removable portions thereof;

FIG. 2 is a side elevation view thereof, the opposite side being identical;

FIG. 3 is an end elevation view thereof, the opposite end being identical;

FIG. 4 is a bottom plan view thereof; and,

FIG. 5 is a top, front, and right side perspective view thereof, with the portions shown in dashed lines in FIG. 3 removed, and with the broken-line disclosure of bottles being for illustrative purposes only and forming no part of the claimed design.

1 Claim, 2 Drawing Sheets
